UNITED STATES PATENT OFFICE.

WILLIAM H. STEVENS, OF NEW YORK, N. Y.

SUSPENDERS.

1,361,113.

Specification of Letters Patent.

Patented Dec. 7, 1920.

Application filed September 26, 1918. Serial No. 255,784.

To all whom it may concern:

Be it known that I, WILLIAM H. STEVENS, a subject of the King of Great Britain, residing at New York, in the county of New 5 York and State of New York, have invented certain new and useful Improvements in Suspenders, of which the following is a specification.

The principal object of this invention is 10 to provide a construction of suspenders in which the back strap, which is to be secured to two buttons at the back of the waistband of the trousers, as usual, is a single length of preferably elastic fabric threaded through a 15 connecting member of such construction and in such manner that the fabric is held substantially immovable in the connecting member under ordinary conditions of use, though it may be readily adjusted therein when desired; and to provide further for making the 20 shoulder strap part of the suspenders of a single piece of fabric threaded through the same connecting member in such manner that it will be slidable therein to allow for various 25 bending movements of the wearer in use.

Other objects and aims of the invention, more or less broad than those stated above, together with the advantages inherent, will be in part obvious and in part specifically 30 referred to in the course of the following description of the elements, combinations, arrangements of parts, and applications of principles constituting the invention; and the scope of protection contemplated will 35 appear from the claims.

In the accompanying drawings, which are to be taken as part of this specification, and in which I have shown a merely preferred form of embodiment of the invention, Figure 40 1 is an elevation of a pair of suspenders embodying my invention; Fig. 2 is an enlarged view in elevation illustrating the connecting member, with the back strap and shoulder strap parts threaded through it, 45 looking at one side of the connecting member; Fig. 3 is a similar view looking at the other side of the connecting member; Fig. 4 is a sectional view taken on the line 4—4 of Fig. 2; Fig. 5 is a sectional view taken on the line 5—5 of Fig. 2; Fig. 6 is a view 50 similar to Fig. 2 illustrating another form of connecting member, looking at one side of the article; Fig. 7 is a view similar to Fig. 6 looking at the other side of the article; 55 Fig. 8 is a sectional view taken on the line

8—8 of Fig. 6; Fig. 9 is a plan view of the form of connecting member shown in Figs. 6, 7, 8; and Fig. 10 is a view similar to Fig. 9 and illustrating the form of connecting member shown in Figs. 1, 2 and 3. 60

Referring to the numerals on the drawings and first to Figs. 1 to 5 inclusive and 10, the numeral 11 indicates the back strap of a pair of suspenders, comprising a single length of preferably elastic 65 fabric, having its ends formed with button-holes 12. This back strap is threaded through a connecting member 14 shown in detail in Fig. 10. This connecting member comprises a flat frame of suitable material, 70 as for instance metal or celluloid, provided at the top with two parallel slots 15 and 16, defining a cross-bar 17 between them, while 18 indicates a cross-bar which constitutes the upper end of the frame, defined on one 75 side by the upper slot 15. Below the slots 15 and 16 I provide in the frame a pair of slots 19 and 20, which diverge from the bottom of the frame toward the top. The back strap is threaded through this frame as 80 shown in Figs. 1, 2 and 3. Referring to Fig. 2, in which the parts are shown as they will appear when on the person, the back strap 11 is threaded through the slot 19 from the inner face of the connecting member, thence 85 over the outer face of the connecting member, thence through the upper slot 15 from the outer face of the connecting member, thence over the inner face of the cross-bar 17 of the connecting member, thence from 90 the inner face of the connecting member through the slot 16 to the outer face of the connecting member, and thence over the outer face of the connecting member but under the course 21 of the fabric and from 95 the outer face of the connecting member through the second diverging slot 20 to the inner face of the connecting member. The result of this threading of the fabric, because of the inherent resiliency of the material of which the connecting member is made, which is enhanced by the manner in which it is slotted, is that once the back strap is placed in position as shown in Figs. 1, 2 and 3, it is substantially fixed in the 100 connecting member under ordinary strains of use, it being understood of course that the various slots will be of a width proportioned to the thickness of the fabric so that when the fabric is threaded through the slots 110

it will not be readily slidable therein. The upper slot 15 of the frame is however made somewhat wider than the parallel slot 16 because it is intended to accommodate the shoulder strap portion 22 of the suspenders preferably a single length of non-elastic fabric, which slides readily back and forth through the slot 15 in accordance with the carrying movements of the shoulders of the 10 wearer. This shoulder strap portion is provided with the usual adjusting buckles 24 in which the ends 25 of the strap may be adjusted for length, and in the loops of the strap ends formed between the adjusting 15 buckles 24 and the ends of the strap 22 are secured the usual fitments 26, through which may be threaded the double-ended straps 27 for attachment for buttons at the front of the trousers, all as shown in Fig. 1. The 20 result of this construction is that the back strap provides the necessary stretch and give to the article though the back strap is itself immovably held in the connecting member; while the shoulder strap portion is readily 25 slidable through the connecting member, allowing for movements of the shoulders of the wearer.

The form of device shown in Figs. 6, 7, 8, and 9 is similar to that already described, 30 except that instead of having two slots 19 and 20 there is provided at the bottom of the frame a single slot 28. In this form of device the back strap, which is a single length of material, as before, is threaded 35 through the lower wide slot 28 from the inner face of the connecting member 29 (referring to Fig. 6), thence over the outer face of the connecting member through the upper wide slot 15 to the inner face of the 40 connecting member, thence over the inner face of the cross-bar 17 through the second slot 16 to the outer face of the connecting member but under the course 30 of the strap, and thence through the bottom wide slot 28 to the inner face of the 45 connecting member. The result of this bending of the strap through the various slots and the super-position of the course 30 over the course 31 is to hold the strap 50 firmly in the connecting member, the slots being wide enough to permit of a general diverging of the strap from the portion which is in the upper slot 15 toward its ends. As in the other form of the device, the shoul-

der strap portion 22 is threaded through the 55 upper wide slot 15 and is slidable therein.

Inasmuch as many changes could be made in the above construction, and many apparently widely different embodiments of my invention could be made without departing 60 from the scope thereof, it is intended that all matter contained in the above description or shown in the accompanying drawings shall be interpreted as illustrative and not in a limiting sense. 65

It is also to be understood that the language used in the following claims is intended to cover all the generic and specific features of the invention herein described and all statements of the scope of the invention, which, as a matter of language, might be said to fall therebetween. 70

I claim:—

1. Suspenders including a connecting member comprising a flat frame with three 75 slots formed therein, a back strap threaded through all of said slots and through one of them twice, and a shoulder strap portion threaded through one of the slots.

2. A connecting member comprising a 80 frame having three parallel slots and a back strap comprising a single length of material threaded through the lower one of the slots from one side of the connecting member 85 over the other side of the connecting member through the uppermost one of the slots, to the other side of the connecting member, through the intermediate one of the slots and thence through the lowermost one of the slots, and a shoulder strap portion threaded 90 through the uppermost one of the slots.

3. Suspenders including a connecting member comprising a frame having a plurality of slots formed therein, a back strap threaded through all of said slots and a 95 shoulder strap portion threaded through one of the slots.

4. Suspenders including a connecting member comprising a frame having a plurality of slots formed therein, a back strap 100 threaded through all of the slots with the end portions of said strap diverging in opposite directions from the lower end of the frame, and a shoulder strap portion threaded 105 through the uppermost slot.

In testimony whereof I affix my signature.

WILLIAM H. STEVENS.
